UNITED STATES PATENT OFFICE

GORDON A. SMALL AND JOSEPH J. HENZE, OF DETROIT, MICHIGAN, ASSIGNORS TO A. BACKUS JR. AND SONS, OF DETROIT, MICHIGAN, A CORPORATION OF MICHIGAN

PACKING CRATE

Application filed November 25, 1927. Serial No. 235,489.

The present invention pertains to a novel packing crate, which is designed especially for shipping telephone sets.

The principal object of the invention is to provide a device of this character which may be readily modified to accommodate either the manual or the dial sets. The crate includes a receptacle having blocks on one wall for engaging the base of the set and having on the opposite wall a rack for engaging the head which carries the mouth piece. In the manual set, the stem which carries the head is mounted centrally of the base, and in the dial set somewhat offset from the base, so that there is a different relation between the head and the base in the two sets. The base being fixed by the blocks already mentioned, it becomes necessary to provide an adjustable device for engaging and retaining the head if the device is to be adapted for both kinds of sets. The device of the invention is constructed in accordance with these considerations.

The invention is fully disclosed by way of example in the following description and in the accompanying drawing, in which—

Figure 1 is a bottom plan view of the top wall, showing the adjustable racks;

Fig. 2 is a section on the line 2—2 of Figure 1;

Fig. 3 is a section on the line 3—3 of Figure 2; and

Fig. 4 is a section on the line 4—4 of Figure 2.

Reference to these views will now be made by use of like characters which are employed to designate corresponding parts throughout.

The device includes a box-like receptacle 1 having its upper wall in the form of a removable cover 2. The base 3 of the receptacle has secured thereto a number of retaining blocks 4, so spaced as to receive the base 5 of a telephone set and hold the same against sliding.

The cover 2 is provided with a means for engaging and retaining the head 6 of the set. In the manual set shown in Figure 3, the stem 7 which carries the head extends upwardly from the center of the base, but in the dial or automatic set shown in Figure 4, the stem 7' is somewhat offset from the base 8' in order to accommodate the dial 9. Hence in both cases there is a different relation between the base and the head, and in order to render our invention adaptable to both forms of sets, we mount the head retaining means adjustable relative to the base 3 of the receptacle.

This means consists of racks composed of slats 10 across which are secured spaced parallel end bars 11 and intermediate bars 12. The confronting edges of the bars are formed with opposed notches 13, whereupon the intermediate bars 12 acquire notches at both longitudinal edges as clearly shown in Figure 1. With references to the cover 2, the bars are disposed beneath the slats, and to the lower surface of the cover are secured spacing boards 14 which are engaged by the upper surfaces of the slats. Rails 15 are also secured to the lower surface of the cover in a manner to be slidably engaged by the ends of the slats 10 and to guide the racks in sliding movement transversely of the cover. Each rack is held to the cover by a pin 16 passing through the board 14 and through a slot 17 in one of the intermediate bars 12. The pin is provided at its lower end with a wing nut 18 screwed thereon and thus supporting the rack.

The notches 13 are so formed and arranged that an opposed pair is adapted to receive the head 6 of a telephone set. In order to convert the device from a manual set receptacle to a dial set receptacle, or vice versa, it is necessary to shift the racks a slight distance in order to compensate for the different relations between the head and the base in the two sets. This shifting or adjustment is per-

mitted by the slots 17 in the intermediate bar 12 for accommodating the pin 16, and the adjustment is secured by the nut 18.

When two or more racks are provided, as in Figure 1, a given crate may be used for shipping both kinds of sets. The number of sets accommodated by each rack is governed by the number of intermediate bars 12 comprised in the rack. Figure 1 for example shows two racks of different sizes, so that the crate may carry more of one type than of the other, but it will also be apparent that the crate may be adjusted to carry sets of only one type if desired.

Although a specific embodiment of the invention has been illustrated and described, it will be understood that various alterations in the details of construction may be made without departing from the scope of the invention as indicated by the appended claims.

What we claim is:—

1. A packing crate of the character described comprising a receptacle, retaining blocks secured to one of the inner walls thereof, a rack secured to the opposite inner wall, said rack comprising spaced bars having notches in the confronting edges thereof, slats secured transversely of said bars for maintaining a fixed relation therebetween, and rails secured to said wall and engaging the ends of said transverse slats.

2. A packing crate of the character described comprising a receptacle, retaining blocks secured to one of the inner walls thereof, a rack secured to the opposite inner wall, said rack comprising spaced bars having notches in the confronting edges thereof, rails secured to said wall and engaging said rack and said rack being slidably supported with reference to said last named wall between said rails.

3. A packing crate of the character described comprising a receptacle, retaining blocks secured to one of the inner walls thereof, a rack secured to the opposite inner wall, said rack comprising spaced bars having notches in the confronting edges thereof, slats secured transversely of said bars for maintaining a fixed relation therebetween, and rails secured to said inner wall whereby to engage said transverse slats, said rack being slidably supported between said rails with reference to said last named wall.

4. A packing crate of the character described comprising a receptacle, retaining blocks secured to one of the inner walls thereof, a rack secured to the opposite inner wall, said rack comprising spaced bars having notches in the confronting edges thereof, and slats secured transversely of said bars for maintaining a fixed relation therebetween, said rack being slidably supported with reference to said last named wall, and rails secured to said last named wall and engaging the ends of said slats.

5. A packing crate of the character described comprising a receptacle having a removable cover, retaining blocks secured to the bottom thereof, and adjustable transversely relative thereto, and means for securing said rack in an adjusted position, said rack comprising a plurality of spaced bars extending transversely of said cover and having the confronting edges thereof notched for the purpose described.

In testimony whereof we affix our signatures.

GORDON A. SMALL.
JOSEPH J. HENZE.
